DESIGN FOR A TOY ANIMAL FIGURE

Eli Gordon and Henry Sanders,
Los Angeles, Calif.

Application June 29, 1946, Serial No. 131,170

Term of patent 7 years

(Cl. D34—2)

To all whom it may concern:

Be it known that we, Eli Gordon and Henry Sanders, citizens of the United States, residing at Los Angeles, in the county of Los Angeles and State of California, have invented a new, original, and ornamental Design for a Toy Animal Figure, of which the following is a specification, reference being had to the accompanying drawing forming part thereof.

In the drawing:

Fig. 1 is a side elevation of a toy animal figure, showing our new design;

Fig. 2 is a rear elevation of the toy animal figure, and

Fig. 3 is a front elevation.

We claim:

The ornamental design for a toy animal figure, as shown.

ELI GORDON.
HENRY SANDERS.
